UNITED STATES PATENT OFFICE.

RICHARD A. ENGLEB, OF DUBUQUE, IOWA.

SYSTEM OF ELECTRICAL TRANSMISSION.

1,134,983.

Specification of Letters Patent.

Patented Apr. 6, 1915.

Application filed July 13, 1914. Serial No. 850,627.

To all whom it may concern:

Be it known that I, RICHARD A. ENGLER, citizen of the United States, residing at Dubuque, in the county of Dubuque and 5 State of Iowa, have invented a certain new and useful Improvement in Systems of Electrical Transmission, of which the following is a full, clear, concise, and exact description, reference being had to the accompanying drawings, forming a part of this specification.

My invention relates to systems of electrical transmission and employs a sound producing electric lamp in an operating circuit, 15 means for impressing wave form current upon said circuit to cause varying sound waves and light rays to emanate from the lamp, circuit controlling responsive devices respectively subject to the action of the sound waves and light rays, a receiving responsive device, and a circuit for the receiving responsive device which is jointly controlled by said circuit controlling responsive devices.

25 In the preferred embodiment of the invention the means for impressing wave form current is in the form of a telephone transmitter while the circuit controlling responsive devices desirably reside in a second telephone transmitter which is operated by the sound waves emanating from the electric lamp and a resistance controlling device which is subject to the influence of the light rays emanating from said lamp to change 30 the resistance according to the light rays due to the telephonic current impressed upon the lamp.

I will explain my invention more fully by reference to the accompanying drawings 40 showing preferred embodiments and certain uses thereof but to which embodiments and uses the invention is not to be limited, Figure 1 being a diagram showing a system of circuits and apparatus that constitute one form of the invention; and Figs. 2, 3 and 4, diagrams of modifications of the embodiment of the invention illustrated in Fig. 1.

Like parts are indicated by similar characters of reference throughout the different figures.

50 Referring first more particularly to Fig. 1, there is there illustrated a primary or inducing main telephone circuit that includes a talking battery or other source of suitable current 1, an impedance coil 2, a

lamp 3 supplied with current from the battery 1 and shown in the form of an arco-phone or a speaking arc having carbons 4, a primary winding 5 of an induction coil, and some means for regulating the intensity 60 of the light produced by the lamp for a given flow of current, this means being preferably in the form of a rheostat 6. The means for effecting fluctuation of the current in the main circuit is in the form of a 65 telephone transmitter 7 of usual construction, though the invention is not to be limited to the employment of a telephone transmitter. When this transmitter is spoken into current variations occur in the 70 main circuit because the impedance coil 2 prevents the flow of rapid fluctuations of current through it, there being a corresponding variation of the flow of current through the carbons 4 of the lamp 3. The light at 75 the arc or other light producing center of the lamp varies in response to the variation of current in the main circuit, the lamp producing correspondingly varying sound waves and light rays. The condenser 8 is located 80 in bridge of the main circuit, the battery 1 and rheostat 6 being upon one side of this bridge while the rest of the apparatus which has been so far specifically described is upon the other side of the bridge. This condenser serves to increase the value of the effect produced in the arc. The condensing lens 9 is traversed by varying light rays produced by the lamp while the metallic diaphragm 10 is subject to the varying sound 85 waves produced by the lamp. For the sake of convenience the elements 9 and 10 form component parts of the walls of a housing 11 which is desirably employed for inclosing the lamp. The lens 9 is employed in order 90 that it may concentrate the light rays emanating from a portion of the lamp and direct the same upon a selenium cell 12 or other sensitive medium whose resistance is varied through a wide range upon small 95 variations in the intensity of the light whereby the light may effectively serve to vary the resistance of a circuit throughout a comparatively wide range, to which end the element 12 may be directly included in 100 the circuit whose resistance is thus to be modified in accordance with the variation of light emanating from that portion of the lamp 3 which is individual to the lens 9. The circuit illustrated in Fig. 1 includes, in 105 110

In addition to the selenium cell 12, a primary 13 of an induction coil and a battery 14, or other suitable source of current, for supplying the selenium cell and the circuit including the same with current. A condenser 15 is desirably included in direct shunt of the battery 14 to increase the value of the effects ultimately produced in the primary 13 by the operation of the varying light upon the cell 12.

The sound waves emanating from a portion of the lamp that is individual to the diaphragm 10 impinge upon said diaphragm to vary the intimacy of its constant engagement with a contact 16, thereby to vary the resistance of a circuit in which this diaphragm and contact are included. This circuit contains, in addition to the diaphragm 10 and contact 16, the primary 17 of an induction coil and a battery 18, or other suitable source of current, for supplying the circuit with current. A condenser 19 is desirably included in direct shunt of the battery 18 to increase the value of the effects ultimately produced in the primary 17 by the operation of the varying sound waves upon the diaphragm 10. The primaries 5, 13 and 17 are respectively provided with secondaries 20, 21 and 22. In Fig. 1, these secondaries are shown as being serially included in a secondary circuit that is common to the circuits including the various primary windings. This secondary circuit is shown as also including a winding 23 which is disposed about the permanently magnetized core 24, the elements 23 and 24 being preferably similar to the winding and core of a telephone receiver. Telephonic current impressed upon the main telephone circuit that includes the lamp 3, the varying light and sound waves emanating from the lamp, the current in the circuits including the primary windings 5, 13 and 17, and the current traversing the coils 20, 21, 22 and 23, should be maintained in phase to which end a condenser 25 is serially included in the circuit that contains the coils 20, 21, 22 and 23 to neutralize the lag that would otherwise be due to the self-induction in the magnet winding 23, and closed circuits containing coils 26 and 27 are placed in secondary relation to the primaries 13 and 17 respectively, these closed or auxiliary secondary circuits serving to offset the slight lag that would otherwise be present in the primaries 13 and 17. The slight lag in these primaries would otherwise be due to the fact that the counter M. M. F. produced in the secondaries 21 and 22 would be slightly less than the M. M. F. of said primaries since the winding 23 has effective resistance, the auxiliary secondaries 26 and 27 rectifying this condition. By the entire arrangement described all of the current fluctuations in the various primary circuits are in

phase with the light rays¹⁹ and sound waves of the speaking lamp and also with the variations in the operated transmitter 7.

The circuit arrangement illustrated in Fig. 1 is preferred since each reproducing element has the shortest possible circuit and least resistance accompanied by corresponding greatest percentage of variation of the current flow, though I do not wish to be limited to the inclusion of the main secondary coils in the same circuit nor do I wish to be limited to the inclusion of the auxiliary secondary coils in separate circuits. The receiver that includes the elements 23 and 24 may itself be provided with a diaphragm 28, such as is found in a telephone receiver, and this diaphragm may be in constant though varying engagement with a contact 29. The elements 28 and 29 are contained in the circuit which also includes any suitable agency that is to be controlled by the receiver. This circuit may include an impedance coil 2¹ having a circuit arrangement similar to that of the impedance coil 2, in which event the receiver corresponding to the receiver 24 and controlled by the elements 28 and 29 may have a diaphragm free of a contact to enable the application of such final receiver to the ear. By including the receiver winding 23 in a secondary circuit and causing it to influence the operation of an extraneous device such as the diaphragm 28, such secondary circuit can have the smallest possible and constant resistance most effectively to overcome the impedance in the circuits containing the primary windings.

In the arrangement illustrated in Fig. 2 the elements 10, 16, 12 and 13 are included in serial relation in a circuit path that is in shunt of the impedance coil 2 and consequently in parallel with the circuit path that includes the transmitter 7 whereby current emanating from the battery 1 is supplied to the elements 10, 12 and 16 without the necessity of employing the auxiliary battery 14. In Fig. 2 the primary winding 13 serves the purpose of an impedance coil when the surges of the current are the wrong way. For instance, if the transmitter spoken into increases the current flow then current flow would tend to decrease in the branch talking circuit, a result which is prevented by the impedance furnished by said primary 13. Also, the two secondary currents induced at 20 and 21 would tend to neutralize each other were it not for the impedance furnished by the primary 13. But when the current increases in the main talking circuit and the reaction of the arc of the lamp also causes an increase of current in these circuits, then the secondaries function properly together, that is current flow is allowed in them, thus overcoming impedance. In the system of Fig. 2 current variations tend to be set up in both

the main and secondary talking circuits by the action of the transmitter 7 but it is retarded or choked in the secondary talking circuit, being a surge in the wrong direction, 5 but the variation of the main circuit starts the arc to act to set up a surge in the proper direction in the secondary talking circuits.

Fig. 3 illustrates the primary transmitter 7 and the transmitting elements 12, 10 and 16 in serial relation in the same telephonic circuit, the circuit path that includes these elements being in shunt of the impedance device 2. In the form of the invention illustrated by Fig. 3 the primary coils 13 and 17 15 are replaced by a primary coil 13¹ in inductive relation to a secondary coil 21¹ that replaces the secondary coils 21 and 22.

In the arrangement illustrated in Fig. 4, the primary talking current is impressed 20 upon the speaking lamp by means of an induction coil having a primary 29 included in a closed local circuit with the transmitter 7 and the transmitter battery 30 and a secondary coil 31 included in series with the 25 speaking lamp. In this arrangement the battery 1 is separated from the transmitter 7 and in order that the battery 1 may be maintained in proper association with the speaking lamp the secondary 31 is included 30 in circuit with the lamp through condensers 32. By this arrangement great microphone variations may be secured with the aid of a circuit of small resistance.

While I have herein shown and particularly described the preferred embodiment of my invention I do not wish to be limited to the precise details of construction and circuit arrangement shown, as changes may readily be made without departing from the 40 spirit of my invention, but

Having thus described my invention I claim as new and desire to secure by Letters Patent the following:—

1. A system of electrical transmission including a sound producing electric lamp and its operating circuit; means for impressing wave form current upon said circuit to cause varying sound waves and light rays to emanate from the lamp; circuit controlling responsive devices respectively subject to the action of the sound waves and light rays; a receiving responsive device; and a circuit for the receiving responsive device which is jointly controlled by said circuit controlling responsive devices.

2. A system of electrical transmission including a sound producing electric arc lamp and its operating circuit; means for impressing wave form current upon said circuit to cause varying sound waves and light rays to emanate from the arc lamp; circuit controlling responsive devices respectively subject to the action of the sound waves and light rays; a receiving responsive device; and a circuit for the receiving responsive device

which is jointly controlled by said circuit controlling responsive devices.

3. A system of electrical transmission including a sound producing electric lamp and its operating circuit; a telephone transmitter 70 for impressing telephonic current upon said circuit to cause varying sound waves and light rays to emanate from the lamp; circuit controlling responsive devices respectively subject to the action of the sound waves and 75 light rays; a receiving responsive device; and a circuit for the receiving responsive device which is jointly controlled by said circuit controlling responsive devices.

4. A system of electrical transmission including a sound producing electric arc lamp and its operating circuit; a telephone transmitter for impressing telephonic current upon said circuit to cause varying sound 80 waves and light rays to emanate from the 85 arc lamp; circuit controlling responsive devices respectively subject to the action of the sound waves and light rays; a receiving responsive device; and a circuit for the receiving responsive device which is jointly controlled by said circuit controlling responsive devices.

5. A system of electrical transmission including a sound producing electric lamp and its operating circuit; means for impressing 95 wave form current upon said circuit to cause varying sound waves and light rays to emanate from the lamp; circuit controlling responsive devices respectively in the form of a transmitter operated by sound waves emanating from the lamp; a circuit resistance varying element operable by the varying rays of the lamp to effect changing resistance; a circuit controlled by said circuit controlling responsive devices; and a receiving responsive device controlled by said circuit.

6. A system of electrical transmission including a sound producing electric arc lamp and its operating circuit; means for impressing wave form current upon said circuit to cause varying sound waves and light rays to emanate from the arc lamp; circuit controlling responsive devices respectively in the form of a transmitter operated by sound waves emanating from the arc lamp; a circuit resistance varying element operable by the varying rays of the lamp to effect changing resistance; a circuit controlled by said circuit controlling responsive devices; and a receiving responsive device controlled by said circuit.

7. A system of electrical transmission including a sound producing electric lamp and its operating circuit; a telephone transmitter for impressing telephonic current upon said circuit to cause varying sound waves and light rays to emanate from the lamp; circuit controlling responsive devices respectively in the form of a transmitter operated

- by sound waves emanating from the lamp; a circuit resistance varying element operable by the varying rays of the lamp to effect changing resistance; a circuit controlled by said circuit controlling responsive devices; and a receiving responsive device controlled by said circuit.
8. A system of electrical transmission including a sound producing electric arc lamp and its operating circuit; a telephone transmitter for impressing telephonic current upon said circuit to cause varying sound waves and light rays to emanate from the arc lamp; circuit controlling responsive devices respectively in the form of a transmitter operated by sound waves emanating from the arc lamp; a circuit resistance varying element operable by the varying rays of the lamp to effect changing resistance; a circuit controlled by said circuit controlling responsive devices; and a receiving responsive device controlled by said circuit.
9. A system of electrical transmission including a sound producing electric lamp and its operating circuit; means for impressing wave form current upon said circuit to cause varying sound waves and light rays to emanate from the lamp; circuit controlling responsive devices respectively subject to the action of the sound waves and light rays; a receiving responsive device; a circuit for the receiving responsive device which is jointly controlled by said circuit controlling responsive device; and induction windings interposed between the circuit controlling responsive devices and the circuit for the receiving responsive device.
10. A system of electrical transmission including a sound producing electric arc lamp and its operating circuit; means for impressing wave form current upon said circuit to cause varying sound waves and light rays to emanate from the arc lamp; circuit controlling responsive devices respectively subject to the action of the sound waves and light rays; a receiving responsive device; a circuit for the receiving responsive device which is jointly controlled by said circuit controlling responsive devices; and induction windings interposed between the circuit controlling responsive devices and the circuit for the receiving responsive device.
11. A system of electrical transmission including a sound producing electric lamp and its operating circuit; a telephone transmitter for impressing telephonic current upon said circuit to cause varying sound waves and light rays to emanate from the lamp; circuit controlling responsive devices respectively subject to the action of the sound waves and light rays; a receiving responsive device; a circuit for the receiving responsive device which is jointly controlled by said circuit controlling responsive device and
- induction windings interposed between the circuit controlling responsive devices and the circuit for the receiving responsive device.
12. A system of electrical transmission including a sound producing electric arc lamp and its operating circuit; a telephone transmitter for impressing telephonic current upon said circuit to cause varying sound waves and light rays to emanate from the arc lamp; circuit controlling responsive devices respectively subject to the action of the sound waves and light rays; a receiving responsive device; a circuit for the receiving responsive device which is jointly controlled by said circuit controlling responsive devices; and induction windings interposed between the circuit controlling responsive devices and the circuit for the receiving responsive device.
13. A system of electrical transmission including a sound producing electric lamp and its operating circuit; means for impressing wave form current upon said circuit to cause varying sound waves and light rays to emanate from the lamp; circuit controlling responsive devices respectively in the form of a transmitter operated by sound waves emanating from the lamp; a circuit resistance varying element operable by the varying rays of the lamp to effect changing resistance; a circuit controlled by said circuit controlling responsive devices; a receiving responsive device controlled by said circuit; and induction windings interposed between the circuit controlling responsive devices and the circuit for the receiving responsive device.
14. A system of electrical transmission including a sound producing electric arc lamp and its operating circuit; means for impressing wave form current upon said circuit to cause varying sound waves and light rays to emanate from the arc lamp; circuit controlling responsive devices respectively in the form of a transmitter operated by sound waves emanating from the arc lamp; a circuit resistance varying element operable by the varying rays of the lamp to effect changing resistance; a circuit controlled by said circuit controlling responsive devices; a receiving responsive device controlled by said circuit; and induction windings interposed between the circuit controlling responsive devices and the circuit for the receiving responsive device.
15. A system of electrical transmission including a sound producing electric lamp and its operating circuit; a telephone transmitter for impressing telephonic current upon said circuit to cause varying sound waves and light rays to emanate from the lamp; circuit controlling responsive devices respectively in the form of a transmitter operated by sound waves emanating from the lamp; a circuit resistance varying element operable by the varying rays of the lamp to effect changing resistance; a circuit controlled by said circuit controlling responsive devices; a receiving responsive device controlled by said circuit; and induction windings interposed between the circuit controlling responsive devices and the circuit for the receiving responsive device.

varying rays of the lamp to effect changing resistance; a circuit controlled by said circuit controlling responsive devices; a receiving responsive device controlled by said circuit; and induction windings interposed between the circuit controlling responsive devices and the circuit for the receiving responsive device.

16. A system of electrical transmission including a sound producing electric arc lamp and its operating circuit; a telephone transmitter for impressing telephonic current upon said circuit to cause varying sound waves and light rays to emanate from the arc lamp; circuit controlling responsive devices respectively in the form of a transmit-

ter operated by sound waves emanating from the arc lamp; a circuit resistance varying element operable by the varying rays of the lamp to effect changing resistance; a circuit controlled by said circuit controlling responsive devices; a receiving responsive device controlled by said circuit; and induction windings interposed between the circuit controlling responsive devices and the circuit for the receiving responsive device.

In witness whereof, I hereunto subscribe my name this 9th day of July A. D. 1914.

RICHARD A. ENGLER.

Copies of this patent may be obtained for five cents each, by addressing the "Commissioner of Patents, Washington, D. C."

It is hereby certified that in Letters Patent No. 1,134,983, granted April 6, 1915, upon the application of Richard A. Engler, of Dubuque, Iowa, for an improvement in "Systems of Electrical Transmission," an error appears in the printed specification requiring correction as follows: Page 4, lines 21-22, strike out the words and semicolon "and a receiving responsive devices;" and that the said Letters Patent should be read with this correction therein that the same may conform to the record of the case in the Patent Office.

Signed and sealed this 20th day of July, A. D., 1915.

[SEAL.]

R. F. WHITEHEAD,
Acting Commissioner of Patents.
